UNITED STATES PATENT OFFICE.

WARREN B. WHITE, OF NORTH ABINGTON, MASSACHUSETTS.

METHOD OF MAKING TACKLESS MCKAY SHOES.

Application filed October 31, 1921. Serial No. 511,590.

My present invention is an improvement in the art of manufacturing boots and shoes, and more particularly relates to a method of making tackless McKay shoes.

5 The present improvement is directed primarily to the manufacture of that class of footwear known as McKay, sewed or fastened by "through and through" stitching, and has for its object the production by 10 novel, simple and efficient methods, of a tackless McKay shoe. Heretofore in the manufacture of McKay sewed shoes it has been customary to make these shoes upon a last with a clinching plate along the bot- 15 tom, to apply an insole to the shoe of sufficient strength to receive and hold the lasting tacks clinched therein, which tacks were driven from the outside through the insole and clinched against the bottom of the last 20 during or as a part of the lasting operation. These tacks were left permanently in the shoe, it being necessary to so leave them while the last was pulled and the McKay stitching applied, attaching the outsole to 25 both insole and upper materials. This method has been very objectionable, because the lasting tacks were left in the shoe where they frequently worked loose, to the dis- 30 comfort of the wearer and furthermore a shoe construction resulted which was ex- tremely stiff and unbending, whereas a shoe with considerable flexibility is desired.

My present invention contemplates the entire removal of the lasting tacks or equiv- 35 alent upper holding devices from the shoe, after the outsole has been stitched thereto. Furthermore, I am enabled to carry out my method of shoe manufacture by the usual steps and utilizing the present well known 40 machines in general use in shoe factories, without the addition of other machines or cumbersome processes. By removing the lasting tacks after they have performed their function of holding the lasted upper and in- 45 sole together while the last is removed and the permanent stitching applied, I am en- abled to produce a shoe by a very simple McKay sewed process which will be as flex- 50 ible as a welt or turn shoe.

55 In carrying out my invention I prefer to prepare the insole, or insole member, which may be either left in the shoe or a part per- manently removed therefrom, as will be ex- plained, with the equivalent of lasting tacks but applied thereto and carried thereby in a directly reverse manner from that ordi- 60 narily in vogue, i. e., in prior shoe con- structions the lasting tacks were driven in from the outside through the insole and clinched against the last. In my present 65 construction I apply the upper holding tacks or members, which may be termed tacks, directly to the insole or inner member carrying them with the points projecting up- wardly and the heads resting against the 70 last. Thus these tacks are never driven into a last and neither is any clinching plate required on the bottom of the last, thus per- mitting unlimited re-use of a wooden last without damage thereto by the lasting tacks. 75 With the insole or insole member thus pre- pared I apply it to the last with the points projecting upwardly, then pull over and catch the upper thereto, this being accom- plished by the usual Hand Method lasting 80 machines, or by hand, and if desired, these projecting points may be of sufficient length to clinch slightly over the upper. There- upon the outsole is applied, the last with- drawn and the McKay stitching inserted. 85 The lasting tacks having now served their function of holding the upper in lasted position until the McKay stitching was applied, are no longer necessary in the shoe. At this point I remove these lasting tacks. In car- 90 rying out this operation of tack removing, various methods may be used. For example I contemplate applying the tacks through a strip of carrying material of sufficient strength to enable the entire row of lasting 95 tacks along the margin of the insole, to be pulled out and extracted. Furthermore I may remove that part of the insole-like member carrying the tacks, entirely if de- 100 sired, after the McKay stitching, in the lat- 105 ter instance setting the stitching outside of the margin of the said part of the insole or lasting-tack-carrying member, thereby leav- ing the outsole and upper materials united and presenting a shoe construction substan- 110 tially equivalent to that of a turn shoe, with- out the turning. A further modification would be in cutting a portion of the insole or tack carrying member and removing the same or in raising the forepart of the insole, extracting the tacks and replacing the insole free of tacks back in the shoe. These vari- 115 ous modifications will be hereinafter more fully described.

It is believed that the preparation of an insole with lasting tacks positioned in the manner heretofore described, is a distinct

novelty and I have claimed the same in my Patent 1,557,639 dated October 20, 1925.

It is further believed that the improved boot or shoe as an article of manufacture, and made by my novel process, is a novelty in this art and I have claimed the same in my Patent 1,522,564 dated January 13, 1925.

An additional and important feature of my invention consists in the novel idea of having the insole, or insole-like member, either formed with a plurality of sections, or capable of being cut while on the shoe and last into a plurality of sections, one of which sections may thereafter be withdrawn to release the same from the lasting tacks or tacklike holding devices.

Referring to the drawings, illustrating preferred embodiments of the invention,

Fig. 1 is a plan view of my insole, or insole member, prepared with the last engaging tacks or devices therein, and showing the grain surface of the insole adapted to be positioned next the last, with the tack heads in contact with the last;

Fig. 2 is a fragmentary portion of the reverse or flesh side of the insole, showing the lasting tack points projecting upwardly; and

Fig. 3 is a cross-sectional view on the line 3-3 of Fig. 2;

Fig. 4 is a plan view similar to Fig. 1, illustrating a modified method;

Fig. 5 being a corresponding similar view illustrating a still further modification;

Fig. 6 is also a plan view of the insole or insole member, wherein a plurality of tack carrying strips are employed;

Fig. 7 is a cross-sectional view on the line 7-7 of Fig. 6, and showing the completed shoe with the outsole attached and the lasting tacks ready to be removed;

Fig. 8 is a cross-sectional view on the line 8-8 of Fig. 5, further illustrating that construction;

Fig. 9 is a cross-sectional view of a shoe on a line approximately 9-9 of Fig. 4;

Fig. 10 is a cross-sectional view of my general shoe construction, before the lasting tacks are removed;

Fig. 11 is a fragmentary view of the tack carrying strip;

Figs. 12, 13 and 14 being further modifications of lasting devices.

As shown in Figs. 1, 2 and 3, I first prepare an insole, designated generally at 1, cut away at the marginal portion from the toe to heel parts, indicated in dot and dash line at 2, 2. This construction permits the through and through stitching along the forepart and shank to be set free of engagement with this part of the insole, if desired, and therefore leaves this part of the insole free to be raised or pulled out after the shoe is made, the last removed and the outsole

stitching inserted. For this purpose it is necessary to also cut the insole—where the toe portion is to be lasted—as indicated at 3, Figs. 1 and 2. This cut at 3 may be made and the remainder of the insole cemented to its toe portion and then the lasting tacks or devices 5, 5, are put through from the grain side of the insole, i. e., that intended to be next the foot of the wearer, with their points 6 projecting therefrom. The insole thus prepared is then applied to the last, with the heads of the tacks or lasting fastening devices 5, in contact with the last, and the points 6 projecting upwardly. The upper is then assembled, pulled over and lasted by catching upon the points 6. I find that this is a feasible method of lasting a shoe, and can be accomplished either by hand or by the well-known Hand Method

lasting machine, the machine being operated in the same manner as now customary, excepting that the tack reservoir and raceway are removed or the tack reservoir simply not filled, the driving bar effectually serving to hammer down the upper after the lasting fingers have stretched and pulled over the same. Then, with the upper thus lasted, I apply the outsole, withdraw the last, and put through the through and through stitching, which engages the outsole and upper along the dotted line 10, in Fig. 1, just missing the inside of the insole from the points 11 to 12, i. e., toe to heel, and stitch through the toe and heel portions—if desired. The shoe as thus made is then in the position as shown in Fig. 10, wherein the outsole 15 is attached to the upper materials 16 by the outsole stitching 17, which latter is set through outside the marginal edge of the insole 1. The toe and heel portions may be tacked or nailed after being lasted in the usual manner. As shown in Fig. 1, the dot and dash line 2 illustrates practically the line of the last, and therefore the upper is drawn over beyond the same and spaced thus far from the marginal edge of the insole 1. With the upper thus secured to the outsole, it is then feasible to reach into the shoe, and with a sharp instrument, pinchers or the like, catch the rear portion of the insole along the line of cut 3, and pull the same out, thus releasing the tacks from their engagement with the upper.

The part of the insole at the rear of the toe portion can be pulled out of the shoe until only the heel retaining nails retain the same, and thereupon the lasting tacks 5 can be readily removed from the insole. The insole may be then replaced and left in the shoe, or if desired, may be cut off, either across the ball of the shoe at 18, or at the heel portion at 19, Fig. 1, and thereupon the shoe will be left in the position as illustrated in Fig. 9.

My invention of thus cutting the insole

or having the same in severable sections, enables the insole to carry the lasting tacks until the shoe is completed, after which it may be removed.

5 The construction illustrated in Fig. 5 shows a further modification, wherein the insole 25, instead of being so formed and constructed in sections as to permit of part of the insole being pulled out from the inside of the shoe after the outsole stitching is otherwise completed, is made of a complete size, and is adapted to have the through and through stitching 30 engage the insole entirely around the same, as illustrated in Fig. 8. In this form I either cut or provide removable sections carrying the tacks, these sections being designated at 33, 33, and extending from the toe portion to adjacent the heel, carrying the tacks 5, 5. 10 These sections may be cut on a bevel and then cemented to the insole 25, or the insole 25 may be first tacked to the last after the tacks 5 have been inserted therethrough, and then the sections 33, 33, cut with a knife 15 almost through, to permit the subsequent removal of these entire sections of the insole after the shoe is otherwise complete. In this form the tack carrying strip or portion of the insole is removed.

20 I prefer to also have separate tack carrying strips, this form being illustrated in Figs. 6 and 7. Under this arrangement the insole 40 may be either of a full width of the last, and therefore adapted to receive the stitching 41, in accordance with usual 25 McKay shoe construction, or the insole may be cut away along its marginal part similar to that shown in Fig. 4, to leave a loose-footed insole from toe to heel, for greater 30 flexibility. As illustrated in Fig. 7, I have shown these tack carrying strips 44 with the tacks 5 therein, of suitable length to extend along the forepart and shank, i. e., from toe to heel, and to remain in position until 35 after the upper is lasted thereover. Thereupon the outsole is applied, the last removed and the through and through stitching 41 put in, engaging both insole, upper and outsole and permanently securing the shoe together. The shoe being now completed, the strips 44 can readily be removed by pincers, sharp instrument or the like, thus withdrawing the tacks entirely from the forepart and shank of the shoe, and leaving the same free 50 of metallic fastening, thus forming a tackless McKay shoe construction.

55 Figs. 12, 13 and 14 illustrate tacks strips 48 and 50, carrying thereon various types of metallic fasteners 51 and 52 to take the place of the tacks 5, or as a substitute therefor. These fastening devices are, of course, optional, but in each instance present points upwardly, and are so attached to the strips 48 and 50 as to insure their positive removal

from the shoe. Furthermore, where the 65 projecting points are comparatively short and do not project beyond the thickness of the upper material 16 lasted thereon, these strips could readily be used repeatedly in successive shoe manufacturing operations. 70 Even should the driving bar clinch slightly the points or an occasional point, these could be readily removed from the shoe when the strips are torn out and a new 75 tack or fastener could be placed on the strip in order to enable the strips to be used subsequently.

80 My invention is further described and defined in the form of claims as follows:

1. The improved method of making boots and shoes employing McKay stitching, which consists in providing an insole of less dimensions than the inside of the shoe, fixing through said insole a plurality of upper holding metallic members with the points 85 projecting uppermost from the tread surface thereof, assembling the insole and upper materials on a last, lasting the shoe by pulling over, stretching and engaging the upper materials onto said metallic members, applying the outsole, removing the last, stitching through outsole and upper materials beyond the marginal edge of a portion of the insole, and then removing the said metallic members by withdrawing the same from inside 90 the shoe.

95 2. The improved method of making boots and shoes employing McKay stitching, which consists in providing an insole of less dimensions than the inside of the shoe, fixing through said insole a plurality of upper holding metallic members with the points 100 projecting uppermost from the tread surface thereof, assembling the insole and upper materials on a last, lasting the shoe by 105 pulling over, stretching and engaging the upper materials onto said metallic members, applying the outsole, removing the last, stitching through the outsole and upper materials beyond the marginal edge of a portion of the insole, and then removing that 110 part of the insole carrying said metallic members.

115 3. The improved method of making a tackless McKay shoe, consisting in positioning removable lasting tacks in an insole so as to be carried thereby and extend therethrough, assembling said insole on a last with the tack heads bearing on the last bottom and the points projecting from the insole in position to engage and hold the upper when lasted, lasting the upper, applying the outsole, withdrawing the last, sewing the shoe, and then removing a part of the said insole and the tacks carried thereby. 120 125

In testimony whereof, I have signed my name to this specification.

WARREN B. WHITE.
